DESIGN FOR A HANDLE BAR GRIP FOR BICYCLES OR THE LIKE

Ewald F. Pawsat, Maysville, Ky., assignor to
Wald Manufacturing Company, Incorporated,
a corporation of Kentucky

Application March 23, 1938, Serial No. 76,033

Term of patent 14 years

To all whom it may concern:

Be it known that I, Ewald F. Pawsat, a citizen of the United States, residing at Maysville, in the county of Mason and State of Kentucky, have invented a new, original, and ornamental Design for Handle Bar Grips for Bicycles or the like, of which the following is a specification, reference being had to the accompanying drawing, forming a part thereof.

In the drawing:

Figure 1 is a side elevation of a handle bar grip showing my new design;

Figure 2 is a top plan view of said handle bar grip;

Figure 3 is an end elevation of the handle bar grip.

I claim:

The ornamental design for a handle bar grip for bicycles or the like, as shown.

EWALD F. PAWSAT.
